Walter E. Hallam

by Geo. N. Goddard, Atty.

UNITED STATES PATENT OFFICE.

WALTER E. HALLAM, OF PAWTUCKET, RHODE ISLAND.

LINGERIE-CLASP.

1,385,614.

Specification of Letters Patent. Patented July 26, 1921.

Application filed January 24, 1920. Serial No. 353,682.

To all whom it may concern:

Be it known that I, WALTER EARL HALLAM, a citizen of the United States, and resident of Pawtucket, in the county of Providence and State of Rhode Island, have invented certain new and useful Improvements in Lingerie-Clasps, of which the following is a specification.

This invention relates to lingerie clasps and is intended to provide a clasp of that character so constructed that it will afford simple and effective means to prevent slip or displacement of the clasp from its proper position when in use in the garments.

15 The invention consists primarily in a spring clasp formed by reversely bending a strip of metal upon itself to form approximately parallel arms turning in interlocking hooked or curved ends, one of said arms being formed with opposed spring lips whose flexibility is secured without sacrifice of strength or durability by the peculiar arch like construction as will be hereinafter explained.

25 In the accompanying drawings I have illustrated the preferred form embodying the principles of this invention, in which—

Figure 1 shows the flat metallic blank out of which the complete clasp is formed.

30 Fig. 2 is a side elevation showing the complete clasp in locked position as it appears when in use.

Fig. 3 is a side elevation showing the clasp in open position ready to be applied to the garment.

35 Fig. 4 is a central cross sectional view of the clasp.

In the practice of my invention according to the form illustrated in the drawings a 40 metallic strip α of sufficient length is cut or died out so as to form a pair of opposed lateral wings b located approximately one quarter of the entire length from one end of the blank. These wings b preferably have 45 their outside edges curved as shown and have their interior portions cut out to form central openings b' .

The blank α is then formed or bent by suitable dies into the conformation shown 50 in Figs. 2 and 3 by forming the two ends into curved hook like members α' α'' so disposed that one will spring over and clasp the other so as to keep the clasp closed or locked.

55 The perforated wings b are bent to a substantially right angle position with relation to the arm of the clasp in which they are

formed but preferably with a slight concavo-convex curvature, as shown in Fig. 4. It will thus be seen that each lateral edge of the lever arm of the clasp is provided with an arch shaped wing which by reason of its central perforation at b' and the slight lateral or inward curve is given a substantial degree of resiliency while preserving its strength and durability. Moreover with 60 this construction no sharp point is left to penetrate and get caught in the fabric so as to produce injury in the effort to disengage the clasp from the fabric. The resiliency of this bowed and perforated construction 65 allows the clasp to accommodate itself readily to variable thicknesses of fabric while at all times pinching the fabric between the wings b and the opposed arm of the clasp so as to maintain the clasp in the desired position. The gradual or easy slope of the 70 edges of the upturned wings facilitates the easy application to and removal from the fabric, and serves also to spread the interposed fabric evenly throughout the length 75 of the clasp thus tending to avoid bunching or wrinkling the fabric.

What I claim is:

1. A lingerie clasp comprising an elongated strip of flexible material reversely curved at its middle portion to form two approximately parallel hooked arms and having formed on the opposite lateral edges of one arm a pair of opposed curvilinear wings provided with central apertures, substantially as and for the purpose described.

2. A lingerie clasp comprising two integrally formed approximately parallel clasp arms one of which is formed at the middle portions of its opposite edges with resilient curved wings projecting toward the other arm to yieldingly pinch the interposed fabric against said other arm, substantially as described.

3. A lingerie clasp comprising two co-operating longitudinal arms integrally united at one end and having their free ends formed to effect an interlocking engagement with each other, one of said arms being provided on its lateral edges with integrally formed perforated wings disposed at an angle to the plane of said arm and inwardly bowed toward each other, substantially as described.

4. A lingerie clasp comprising an integral strip of material reversely bent to form opposed arms adapted to interlock at their free

ends, one of said arms having upturned and laterally curved perforated wings located at its opposite edges to form resilient means for yieldingly pinching the interposed fabric 5 against the other arm, substantially as described.

5. A lingerie clasp comprising an elongated strip of flexible material formed into two approximately parallel interlocking 10 arms, one of which has formed integrally at its opposite side edges arch shaped resilient wings arranged in opposition to each other and adapted to yieldingly pinch the interposed fabric against the other arm of the 15 clasp without piercing the fabric, substantially as described.

6. A lingerie clasp embracing in its construction two approximately parallel interlocking arms integrally united by a connecting bend, one of said arms being formed with 20 laterally projecting perforated wings extended beyond the parallel edges of the arm and turned to stand at approximately right angles to the plane of said arm, each wing having its middle portion bowed inwardly 25 intermediate of its base and its middle edge portion to form resilient fabric pinching means.

In witness whereof I have subscribed the above specification.

WALTER E. HALLAM.
